(CL. D58—26)

Fig. 1

To all whom it may concern:

Be it known that I, Elsie J. Hagen, a citizen of the United States, residing at Burlington, in the county of Racine and State of Wisconsin, have invented a new, original, and ornamental Design for a Holder for Jars or the like, of which the following is a specification, reference being had to the accompanying drawing, forming a part thereof.

Fig. 1 is an elevational view of a holder for jars or the like showing my new design; and

Fig. 2 is a top plan view thereof.

The sides of the holder not shown are the same as those shown.

I claim:

The ornamental design for a holder for jars or the like, as shown and described.
